UNITED STATES PATENT OFFICE.

EUGENE H. H. SMITH, OF NEW YORK, N. Y.

DESIGN FOR A KNIFE.

Application filed May 23, 1925. Serial No. 13,551. Term of patent 14 years.

To all whom it may concern:

Be it known that I, EUGENE H. H. SMITH, a citizen of the United States, residing in the city, county, and State of New York, have invented a new, original, and ornamental Design for a Knife, of which the following is a specification, reference being had to the accompanying drawing, forming a part thereof.

I claim:

The ornamental design for a knife, as shown.

EUGENE H. H. SMITH.
